UNITED STATES PATENT OFFICE.

WILLIAM B. ROBINS, OF CINCINNATI, OHIO, ASSIGNOR TO THE ALBA LIGHT COMPANY, OF SAME PLACE.

LAMP.

SPECIFICATION forming part of Letters Patent No. 269,466, dated December 19, 1882.

Application filed June 21, 1882. (No model.)

To all whom it may concern:

Be it known that I, WILLIAM BURNET ROBINS, of Cincinnati, Hamilton county, Ohio, have invented a new and useful Lamp, of which the following is a specification.

My lamp is more particularly intended for use with kerosene and kindred forms of petroleum and coal oils, and has for its leading objects economy of material with high illuminative properties and convenient and cleanly manipulation of wick, together with complete safety.

In the accompanying drawings, Figure 1 is a partially-sectioned elevation of a lamp embodying my improvements. Fig. 2 is a top view of the same without its shade, central deflector, and chimney, the base of the standard being omitted. Fig. 3 is an external view of the needle-rack column or housing, and portions of the font and its supporting inverted siphon. This figure contains a sectional representation of an adjustable form of my shade-bracket, of which Fig. 4 is a top view. Figs. 5 and 6 are sections of the rack-housing at 1 1 and at 2 2, respectively. Fig. 7 shows the wick-carrier and holder detached, a portion of the wick-elevating "needle" being seen attached to the carrier.

A pedestal of suitable height and dimensions affords support to the inverted siphon 30 B, whose longer arm b communicates with and supports, in a sufficiently-elevated position, the font or reservoir C, from whose floor, where it communicates with said siphon, rises a hollow column or housing, D, for a rack, E, which 35 is guided to a vertical path by the walls of said housing and by partition F. A pinion, G, journaled in said housing and having a handle, H, external thereto, enables vertical shifting of the rack at discretion of the user. Soldered or otherwise permanently attached to the said rack is a steel rod, I, called by me the "needle." This rod occupies the inverted siphon or oil-duct B, and protrudes through both ends of the same, and has its other extremity 40 soldered or otherwise permanently fastened to a short tube, J, which I call the "wick-carrier." The wick-carrier J has a flange, j, that projects horizontally from its upper edge, and has two diametrically-opposite notches j', (of which 45 50 one only is here shown,) for reception of hooks

l from similarly-flanged lower end of a similar but longer tube, L, which I call the "wick-holder." This tube has preferably a congeries of orifices, l', near its lower end. To the holder L is fastened a suitable tubular wick, 55 M. The wick, with its holder and carrier, and attached extremity of the operating-needle, occupy and play vertically within an annular wickway, N N' N'', which is soldered or otherwise rigidly fastened to the upturned shorter limb b' of the inverted siphon B. Of the two concentric tubes that constitute the walls of the wickway, the inner tube, N'', constitutes the outer wall of annular draft-inlet O, whose inner wall is constructed as follows: A bridge, 60 65 P, which stretches athwart the lower end of the tube N'', supports, coincident with its axis, a tube, Q, of rather smaller diameter.

Over the tube Q is slipped a closely-fitting tubular cap, R, which, being crowned by a 70 projecting disk, S, operates to deflect toward the annular sheet of flame the annular current of air from the draft-inlet O. Pins T or any other suitable provision upon either tube Q or R prevent the cap R descending below 75 its proper position for efficient service as deflector.

A gallery or collar, U, which encircles the wickway, has numerous minute orifices u to admit draft-air to the outer draft-inlet, V, 80 whose inner wall is formed by the outer tube, N, of the wickway, and whose outer wall is formed by the truncated hollow cone W, which rests upon said gallery U. A shoulder, w, on cone W serves as a resting-place for a glass 85 chimney, X, of any proper form. This construction is exceptionally free from liability to spillage of oil, wick fragments, &c.; but for abundant security a drip pan or catcher, Y, may be affixed to the oil-duct B.

The rack-holder or housing D may be utilized for attachment of a bracket, 1, to which is secured by hinge 2 an elastic clasp, 3, for suspension of a shade or reflector, 4. The hinge 2 permits the clasp 3 and its appended 95 shade 4 to be folded back to position shown by dotted lines in Fig. 1 when desired.

The bracket 1 may be immovably attached to the housing D, as in Fig. 1, or may be made capable of sliding up and down upon it, and of 100

being secured at any desired elevation by set-screw 5, as in Figs. 3 and 4.

The location of the wick-operating handle remote from and out of the vertical line of the burner entirely avoids any heating or soiling of the handle, and reduces to a minimum impediments to the free radiation of light, whether from the user's hand or otherwise, while the similarly-isolated location of the font avoids 10 any dangerous heating of its contents.

The described form and arrangement of concentric tubes and disk-deflector, which cause the interior air to rise at first in a uniform annular cylinder or sheet, and subsequently to 15 project radially and obliquely upward toward the interior wall of the flame-sheet, coaxing with the obliquely inward and upward annular draft-sheet from the outer deflector, are found to produce an intensely white and re- 20 markably even flame.

The removability of the tubular cap or thimble R S enables the easy trimming of the wick and the cleaning of the central air-passage, and also enables the substitution of a new tu- 25 bu'ar cap or thimble when necessary.

I am aware that annular interior draft-inlets are old and well known, and therefore make no claim to such, broadly considered.

A subsidiary but valuable function of the 30 needle is that of agitating the liquid contents and preventing any lodgment of sedimentary matters.

Besides the effects above mentioned, very 35 important economic results accrue from the presence of the tubular extension R Q from the highly-heated disk or button S. Said tubular extension, being a good conductor, becomes itself highly heated, and operates beneficially, both by preheating the interior annular sheet 40 of draft-air and, operating chimney-wise, in stimulating the atmospheric up-rush, thus causing contact of rapidly following volumes of heated air with the inner face of the flame-sheet. The thus heated air is further benefi- 45 cial in that it raises the temperature of the oil within the wickway, and, by expanding and partially vaporizing it, facilitates its combustion.

The described mounting of wick-tube by its 50 extreme lower end upon the extreme delivery end of the J-shaped oil-duct secures the utmost practicable thermal insulation of the wickway by reducing to a minimum the robbing of its heat by said duct, such as always 55 occurs with the customary attachment of the duct at or near the mid-height of the wick-tube. My construction consequently secures two important ends, to wit: First, the heat, being retained in the wick-tubes, rarefies the 60 oil-vapor and air-currents; secondly, wasteful and dangerous overflow of heat toward the

font along the metal connection is reduced to a minimum.

The above-described preferred embodiment of my invention is obviously susceptible of 65 various modifications. For example, the font may have a central sleeve to fit around a vertical stem, and be provided with two or more inverted siphon-ducks radiating from it at different parts of its circumference; or a font with 70 a number of such radiating ducts may have projecting from the middle of its crown a vertical stem terminating in an eye, by which to suspend it from a ceiling; or the font may have one flat side with wall-plate extension to 75 hang onto a column or other fixture.

The described J-formed duct and its contained operating-needle may be associated with a flat wick with correspondingly flat carrier and wickway. 80

I claim as new and of my invention—

1. In combination with the inverted siphon-pipe B, connecting the wickway with the oil-font, the flexible rod or needle I, made fast to the wick-carrier and traversing said pipe and 85 font to a point of convenient manipulation, substantially as and for the purpose set forth.

2. The combination, with the inverted siphon-duct B, that connects an elevated font with the wickway, of flexible rod or needle I, 90 which occupies said font, duct, and wickway, and which connects at one extremity with a means for giving it a longitudinal movement, substantially as and for the purpose set forth.

3. In combination with the inverted siphon-duct B, connecting the distant font C with the wickway N N' N'', the font C, provided with the hollow standard D, containing the rack E, carrying needle I, the guide F, pinion G, and operating-handle H, substantially as and for 100 the purposes specified.

4. In combination with the column or housing D, the needle-operating mechanism and the bracket 1, with attached clasp or holder 3 of lamp-shade, substantially as set forth. 105

5. The described combination, with elevated font, inverted siphon-duct, and wickway, of the included wick-operating needle I, and attached rack E, and pinion G, substantially as set forth. 110

6. The wick-tube L, provided with hooks l and orifices l', in combination with the wick-carrier J, having flange j and notches j', and the attached needle I, substantially as set forth. 115

In testimony of which invention I have hereunto set my hand.

WILLIAM BURNET ROBINS.
